UNITED STATES PATENT OFFICE.

LUCIEN H. ARNOLD, OF CHICAGO, ILLINOIS.

TOOTH-BRUSH.

SPECIFICATION forming part of Letters Patent No. 682,836, dated September 17, 1901.

Application filed March 7, 1901. Serial No. 50,202. (No model.)

To all whom it may concern:

Be it known that I, LUCIEN H. ARNOLD, a citizen of the United States, residing in Chicago, in the county of Cook and State of Illinois, have invented a new and useful Improvement 5 in Tooth-Brushes, of which the following is a specification.

I have been led to this invention by the annoyance caused to users of tooth-brushes 10 through the coming loose or falling out of the bristles while the brush is in the mouth; and its object is to prevent the bristles from falling out, thereby lengthening the life of the brushes, as well as avoiding the annoyance 15 referred to.

In my improved brush instead of securing the bristles in any of the methods heretofore in vogue I cut the recesses in the back of the brush in which the tufts or bunches of the 20 bristles are secured in dovetail form—that is to say, with undercut walls or sides—and then secure the bristles therein by combining with them a soft filling, such as tin or lead or other metal or material whose form can be 25 readily changed by pressure. A section of this filling material, which is first reduced to attenuated or wire form, is inserted endwise in each recess with the bristles, either at the time of positioning the latter or subsequently, 30 and is then forced entirely within the recess by pressure applied to its outer end. This causes the material to assume a globular or lump form within the recess, the expansion being in horizontal directions and resulting 35 in forcing the bristles outward and under the undercut walls, so that they are firmly locked in the recess.

The nature of my improvement will be more fully understood from the accompanying 40 drawings, in which—

Figure 1 is an elevation of my improved brush, partly in section. Figs. 2, 3, and 4 are enlarged partial sections, showing a single tuft or bunch and its recess, the first showing 45 the tuft in position ready to receive the filling material, the second showing the material positioned in the tuft, and the third showing it as compressed and locking the tuft.

In said drawings, 5 represents the body or 50 back of the brush, and 6 are the recesses therein for the reception of the tufts or bunches of bristles and having their sides or walls undercut, as plainly shown.

7 7 represent the bunches of bristles which 55 are doubled or bent at their longitudinal cen-

ter preparatory to insertion, as will be understood from the enlarged figures. The filling or locking metal is conveniently reduced to wire form, as this permits it to be inserted in the center of the tuft and below 60 the contracted mouth of the recess, and a section of it is shown as thus positioned at 8 in Fig. 3. After the filling 8 has been positioned, pressure from above is applied to its outer end, and it is thereby compacted into globular 65 or lump form, as seen at 8^a, Fig. 4, in which form it is expanded horizontally to a sufficient extent to force the bristles under the undercut walls. It will be seen that with the filling thus expanded the bristles will be firmly 70 held in the recess, and that they cannot become loose or drop out, and that the locking action will be effective not only to hold the tuft as a whole in place, but that the individual bristles will also be held against dropping out. 75

While the invention has been devised especially for use in tooth-brushes, it will be understood that it may be used in other brushes as well. In tooth-brushes, and perhaps others, 80 the material used for the filling should be able to resist moisture and the acids of the mouth. The invention permits the application of a locking means to the tufts which cannot injure them in any way, and if metal 85 is used it requires neither heat nor moisture.

While I have described the reduction of the filling material prior to insertion to wire or attenuated form, it will be understood that I do not utilize it as a means of forcing 90 the tufts into the recesses, as has been the practice with some of the tuft-fasteners heretofore used. It will also be understood that while the undercutting of the tuft-recesses is advantageous, yet my improved fastener 95 can be used with benefit where the recesses have parallel walls.

I claim—

The brush having its tufts secured in the tuft-recesses by malleable filling material inserted in attenuated form and compressed longitudinally into laterally-expanded lump form within the bends of the tufts and acting to force the bristles outward against the walls of the recesses, substantially as specified. 100

LUCIEN H. ARNOLD.
